(57) **CLAIM**

The ornamental design for a golf tee, as shown and described.

DESCRIPTION

FIG. 1 is a perspective view of the golf tee showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a reduced scale cross sectional view taken along line 8—8 of FIG. 6; and,

FIG. 9 is a reduced scale elevational view showing the design in association with another structure shown in broken lines.

The structure shown in broken lines in FIG. 9 is for illustrative purposes only and forms no part of the claimed design.
